UNITED STATES PATENT OFFICE.

JOSEPH LEONARD, OF ALLENTEWON, PENNSYLVANIA, ASSIGNOR TO FIFTH AVENUE CORSET COMPANY, INC., OF ALLENTEWON, PENNSYLVANIA, A CORPORATION OF NEW YORK.

CORSET.

Application filed September 5, 1925. Serial No. 54,761.

My present invention is an improvement in corsets, and relates to a thigh reducer or thigh controller therefor.

More specifically my present invention is an improvement in the type of corsets or corset brassières disclosed in my prior Patent 1,488,209, of March 25, 1924.

The general object of my present invention is to improve the thigh-controlling feature of my prior invention, by making it adjustable independently of the adjustment of the garment and of the abdominal belt, and vice versa, and further to allow the vertical and longitudinal adjustment of the abdominal belt independently of the adjustment of the thigh controller.

A further object is to improve the thigh-controlling feature by providing for a more effective adaptability thereof to the conformation of the wearer.

With these and other objects in view, which will become more apparent as the description proceeds, the invention resides in the construction, combination and arrangement of parts hereinafter more fully described and claimed.

In the drawings:

Figure 1 is a general view showing a corset brassière in which the invention is embodied.

Figure 2 shows the brassière opened and laid out flat looking on the inside toward the rear.

Figure 3 represents a detailed view of a part of Figure 1, showing parts broken away and other parts folded back, and showing the lacings removed, to more fully illustrate the invention.

Figure 4 is a vertical sectional view of the garment, portions being shown as rolled back for purposes of clearness of illustration.

Although I show and describe the embodiment of the invention in a corset brassière, it will be understood that the invention is equally applicable to a corset.

The garment may be constructed in general substantially as described in my prior patent, and in the description of the garment hereinafter given, I will refer only to those portions which are necessary to give an understanding of the invention.

Referring more particularly to the drawings, the garment in general, includes a soft fabric outer portion 10 which completely

encircles the body. At the sides of the body, the garment is split up to the waist line W-L and the adjacent edges on each side of the splits are provided with eyelets 14, 14 for side lacing connections 15, 15. The elastic section 16, 16 may overlie the upper portions of the split sides.

An abdominal belt 20 has eyelets 21, 21 at its ends, through which the side lacing connections 15 pass for supporting the belt, the same lacings thus supporting the abdominal belt which connect the edges of the garment on each side of the splits together, as shown in my prior patent. As therein also set forth, the ends of the belt are connected with the side lacing connections at such points higher up or lower down as is found most suited to the wearer.

My prior patent shows thigh controlling portions in the nature of elastic thigh sections set in the front adjoining the lower edges of the splits, to provide necessary yielding points when the wearer is seated, and causing the corset to fit the body at a lower point. It also shows the outer edges of the elastic thigh sections as being connected to the adjacent edges of the split sides of the elastic sections which connect the edges of the split sides of the garment together.

My present invention departs from this prior construction with respect to the thigh controlling portions.

According to my present invention the elastic thigh sections 18, which are set in the front 12 of the corset, instead of being connected to the split edges of the garment by the same lacings which secure the adjustment of these edges, are connected by separate lacings 22, not to the split edges of the garment, but to cloth flaps 23. These flaps overlie the lower portions of the sides of the garment, are stitched at their rear edges as at 24 to the sides of the garment, 90 and at their lower edges as at 25, to the side portions of the garment near the lower edges thereof, and the front edges 26, and the top edges 27 of such flaps are left free. The elastic sections 18, together with the flaps 23, with their connections, serve to control the size and fit of the garment around the thigh.

One effect of thus constructing the garment, is to materially increase the length of the thigh controlling portions, by construct-

ing them of the pieces 18 and 23. Another effect is to allow of adjustment of the thigh controlling portions closer together or farther apart, without affecting the adjustment of the sides of the garment or the adjustment of the abdominal belt, and conversely to allow the adjustment of the sides of the garment closer together or farther apart, and of the abdominal belt higher up or lower down, without in any way effecting the adjustment of the thigh controlling portions.

By thus materially increasing the length of the thigh controlling portions, it is found that greater ease and comfort is given to the wearer, and the effectiveness of the garment in following the conformation of the wearer is increased. This increase in length also imparts increased flexibility to the thigh controlling portions, and allows of much more freedom of movement thereof in following the figure in various postures. It also materially decreases the tendency to transmit strains incident to movements of the figure, to the garment. Further the points of attachment of the parts 23 of the thigh controlling portions being along the lines 24, further around to the sides of the garment than the split edges thereof, the pull transmitted to the garment when the thigh controlling portions are closely adjusted, is removed from the split edges of the garment, where the laces 15 occur, and is transferred around to the sides of the garment. Thus the tension on the thigh controlling portions, when they are closely adjusted, or incident to movements or postures of the wearer, will not disturb the adjustment of the sides of the garment, and of the abdominal belt, and these parts can be loosely adjusted at the same time that the thigh controlling portions are closely adjusted, and vice versa. By transferring the pull from the split edges to the sides of the garment, the tendency of the thigh controlling portions, when snugly adjusted to keep the lower portions of the back of the garment in smooth condition, is increased.

Furthermore, by having the thigh sections 18 thus separately connected to the flaps 23, which form extensions of the thigh sections, the eyelets 14 on the sides of the garment, can be extended down, as shown in Figure 3, well below the upper edges 27 of the flaps 23, thus allowing of a lower independent adjustment of the abdominal belt 20.

I have illustrated a front opening garment, but it will be understood that the invention is equally applicable to garments

which open otherwise than at the front, for instance at the side or back.

The foregoing description has been given for clearness of understanding, and no undue limitations should be deduced therefrom, but the appended claims should be construed as broadly as permissible, in view of the prior art.

Having thus described my invention what I claim as new and desire to secure by Letters Patent is:—

1. In a corset having a body portion split adjacent the sides and connected by lacings and having an abdominal belt also connected to said lacings, thigh controlling portions including elastic sections set into the front of the body portion and non-elastic sections over-lapping the lower portions of the sides of the garment, said non-elastic sections being connected to the body portion further around to the sides than the splits, and lacing connections independent of the first said lacings, connecting the sections of each thigh controlling portion together.

2. In a corset having a body portion split adjacent the sides and connected by lacings and having an abdominal belt also connected to said lacings, thigh controlling portions each over-lapping one of the split sides and comprising sections set into the front of the body portion and sections connected to the sides of the body portion of the garment beyond the splits, and lacing connections independent of the first said lacings, connecting the sections of each thigh controlling portion together.

3. In a corset having a body portion split adjacent the sides and connected by lacings and having an abdominal belt also connected to said lacings, thigh controlling portions including sections connected to the front of the body and sections connected to the side portions of the body of the garment, and connections independent of said lacings connecting the sections of the thigh controlling portion together.

4. In a corset having a body portion split adjacent a side thereof and having connections connecting the edges of the split, a thigh controlling portion overlying the lower portion of the split and including a section connected to the front and a section connected to the side of the garment, and connections independent of the first said connections, connecting the sections of the thigh controlling portion together.

In testimony whereof I hereunto affix my signature.

JOSEPH LEONARD.
